UNITED STATES PATENT OFFICE.

CHARLES F. LINDH, OF BROOKLYN, NEW YORK, ASSIGNOR TO STANDARD TOBACCO STEMMER COMPANY, OF NEW YORK, N. Y., A CORPORATION OF VIRGINIA.

TOBACCO-STEMMING MACHINE.

1,188,546.

Specification of Letters Patent. Patented June 27, 1916.

Application filed March 26, 1915. Serial No. 17,094.

To all whom it may concern:

Be it known that I, CHARLES F. LINDH, a citizen of the United States, residing at Brooklyn, county of Kings, and State of New York, have invented a new and useful Improvement in Tobacco-Stemming Machines, of which the following is a specification.

This invention relates to an improvement in tobacco stemming machines.

In certain tobacco stemming machines there is employed an endless chain carrying a series of co-acting two-part stem butt grippers traveling along stemming mechanism and adapted to hold individual leaves by the stem butts while the leaves are acted upon by the stemming mechanism. These grippers are arranged to open at the far end of the stemming mechanism. It sometimes happens that the sticky juices of a tobacco leaf exude from the stem butt and cause it to adhere to one of the parts of a gripper at the time when the same is open and to be thereby carried back where it interferes with an oncoming stem.

One of the objects of the present invention is the production of a device adapted to coöperate with such grippers and to positively eject stems therefrom when the grippers are open and without interfering in any way with their movement.

A further object of the invention is the production of a device which will not only eject a stem but will also clean the adjacent faces of the parts of the grippers; that is to say, to wipe off any sticky juices which may be adhering thereto.

With these and other objects not specifically mentioned in view, the invention consists in certain parts, constructions and combinations which will be hereinafter fully described and then specifically set forth in the claims hereunto appended.

In the accompanying drawings, which form a part of this specification and in which like characters of reference indicate the same or like parts, Figure 1 is a side elevation of a device constructed in accordance with the invention. Fig. 2 is a fragmentary sectional view taken on the line 2-2 in Fig. 1. And Fig. 3 is a detailed end view of the brush shown in Figs. 1 and 2.

In carrying the invention into effect, there is provided a series of co-acting two-part continuously traveling stem butt grippers

said grippers being arranged to open and close in directions coincident with their path of travel, and means adapted to pass between adjacent faces of the parts of said grippers to eject a stem butt sidewise therefrom. In the best constructions means are employed for engaging the adjacent faces of the grippers while open to clean the same. In the best constructions also means are provided for forcing a stem butt out sidewise from between the open gripper parts and to immediately thereafter clean the adjacent faces of the gripper parts. The above elements may vary in construction within wide limits.

In the device selected to illustrate the invention, 4 indicates diagrammatically a sprocket over which runs a chain 5 carrying a plurality of co-acting two-part continuously traveling stem butt grippers 6 which are caused—by mechanism well known in the art—to open to release a stem at a certain point in their path of travel, the direction of the opening and closing of the grippers being coincident with their path of travel. The chain 5 is provided with a series of rollers 7 operating upon a track 8 supported by a main frame 9 of a stemming machine. Since the particular construction of the stemming machine and stem butt grippers lies outside of the present invention, a more detailed description of the same is omitted herefrom in the interest of brevity and clearness. It may be here remarked, however, that they are well known in the art.

Means are provided for ejecting a stem butt sidewise from each gripper while the same is open, and in the device selected to illustrate the invention this means consists of a segmental spiral brush 10 clamped, by means of a screw 11, upon one end of a shaft 12 journaled in a bracket 13 suitably supported from the main frame 9. On the other end of the shaft 12 is fixed a bevel gear 14 which is in mesh with a second bevel gear 15, said second bevel gear being fast upon the upper end of a shaft 16 journaled in the bracket 13 before referred to. The lower end of the shaft 16 is provided with a sprocket 17 over which runs a chain, not shown, but which derives its motion from any suitable moving part of a stemming machine.

The stem butt grippers travel continu-

ously and the segmental spiral brush 10 rotates continuously in a fixed position. The pitch of the spiral is, however, designed to conform to the traveling movement of the 5 stem butt grippers and it is segmental and running idle about one-half of each revolution. During this time, one of the stem butt grippers advances to position to be opened and to have the adjacent faces of its two 10 parts engaged by the brush 10 while so open and while traveling forward. In the event of a stem butt adhering to either of the two parts of a gripper, the leading edge of the spiral or the bristles of the brush carried 15 thereby, will engage the butt and eject it sidewise from the gripper. At the same time, the ends of the bristles of the brush come into contact, the one with the face of one part of a gripper and the other with the 20 face of the other part of the gripper; so that the rotating brush not only ejects a stem butt from a gripper, but performs the further function of cleaning the adjacent faces of the parts of said gripper.

25 Changes and variations may be made in the structure by means of which the invention is carried into effect. The invention therefore is not to be restricted to the precise details of the structure shown and described. 30 Furthermore, certain parts of the invention are capable of use independent of other parts and such independent use is contemplated.

What is claimed is:

1. In a tobacco stemming machine, the 35 combination with a series of co-acting two-part continuously traveling stem butt grippers said grippers being arranged to open and close in directions coincident with their path of travel, of means adapted to pass between adjacent faces of the parts of said grippers while open to eject a stem butt sidewise therefrom.

2. In a tobacco stemming machine, the combination with a series of co-acting two-part 45 continuously traveling stem butt grippers said grippers being arranged to open and close in directions coincident with their path of travel, of means operative in a fixed position and adapted to pass between adjacent faces of the parts of said grippers while open to eject a stem butt sidewise therefrom.

3. In a tobacco stemming machine, the combination with a series of co-acting two-part continuously traveling stem butt grippers 55 said grippers being arranged to open and close in directions coincident with their path of travel, of rotatory means operative in a fixed position and adapted to pass between adjacent faces of the parts of said grippers while open to eject a stem butt sidewise therefrom.

4. In a tobacco stemming machine, the combination with a series of co-acting two-part 65 continuously traveling stem butt grippers said grippers being arranged to open

and close in directions coincident with their path of travel, of a brush adapted to pass between adjacent faces of the parts of said grippers while open to eject a stem butt sidewise therefrom.

5. In a tobacco stemming machine, the combination with a series of co-acting two-part continuously traveling stem butt grippers said grippers being arranged to open and close in directions coincident with their 70 path of travel, of a segmental spiral brush adapted to pass between adjacent faces of the parts of said grippers while open to eject a stem butt sidewise therefrom.

6. In a tobacco stemming machine, the combination with a series of co-acting two-part continuously traveling stem butt grippers said grippers being arranged to open and close in directions coincident with their 75 path of travel, of a segmental spiral brush rotative in a fixed position and adapted to pass between adjacent faces of the parts of said grippers while open to eject a stem butt sidewise therefrom.

7. In a tobacco stemming machine, the combination with a series of co-acting two-part continuously traveling stem butt grippers said grippers being arranged to open and close in directions coincident with their path of travel, of means engaging the adjacent faces of the parts of said grippers while open and adapted to clean said adjacent faces.

8. In a tobacco stemming machine, the combination with a series of co-acting two-part continuously traveling stem butt grippers said grippers being arranged to open and close in directions coincident with their path of travel, of means operative in a fixed position for engaging the adjacent faces of 105 the parts of said grippers while open and adapted to clean said adjacent faces.

9. In a tobacco stemming machine, the combination with a series of co-acting two-part continuously traveling stem butt grippers said grippers being arranged to open and close in directions coincident with their path of travel, of rotatory means operative in a fixed position for engaging the adjacent faces of the parts of said grippers while open 110 and adapted to clean said adjacent parts.

10. In a tobacco stemming machine, the combination with a series of co-acting two-part continuously traveling stem butt grippers said grippers being arranged to open and close in directions coincident with their path of travel, of a brush engaging the adjacent faces of the parts of said grippers while open and adapted to clean said adjacent faces.

11. In a tobacco stemming machine, the combination with a series of co-acting two-part continuously traveling stem butt grippers said grippers being arranged to open and close in directions coincident with their 115

- path of travel, of a segmental spiral brush engaging the adjacent faces of the parts of said grippers while open and adapted to clean said adjacent faces.
- 5 12. In a tobacco stemming machine, the combination with a series of co-acting two-part continuously traveling stem butt grippers said grippers being arranged to open and close in directions coincident with their path of travel, of a segmental spiral brush rotative in a fixed position for engaging the adjacent faces of the parts of said grippers while open and adapted to clean said adjacent faces.
- 10 13. In a tobacco stemming machine, the combination with a series of co-acting two-part continuously traveling stem butt grippers said grippers being arranged to open and close in directions coincident with their path of travel, of means adapted to pass between and engage adjacent faces of the parts of said grippers while open to eject a stem butt sidewise therefrom and to clean said adjacent faces.
- 15 14. In a tobacco stemming machine, the combination with a series of co-acting two-part continuously traveling stem butt grippers said grippers being arranged to open and close in directions coincident with their path of travel, of means operative in a fixed position and adapted to pass between and engage adjacent faces of the parts of said grippers while open to eject a stem butt sidewise therefrom and to clean said adjacent faces.
- 20 15. In a tobacco stemming machine, the combination with a series of co-acting two-part continuously traveling stem butt grippers said grippers being arranged to open and close in directions coincident with their path of travel, of a segmental spiral brush adapted to pass between and engage adjacent faces of the parts of said grippers while open to eject a stem butt sidewise therefrom and to clean said adjacent faces.
- 25 16. In a tobacco stemming machine, the combination with a series of co-acting two-part continuously traveling stem butt grippers said grippers being arranged to open and close in directions coincident with their path of travel, of a segmental spiral brush rotative in a fixed position and adapted to pass between and engage adjacent faces of the parts of said grippers while open to eject a stem butt sidewise therefrom and to clean said adjacent faces.
- 30 17. In a tobacco stemming machine, the combination with a series of co-acting two-part continuously traveling stem butt grippers said grippers being arranged to open and close in directions coincident with their path of travel, of a segmental spiral brush rotative in a fixed position and adapted to pass between and engage adjacent faces of the parts of said grippers while open to eject a stem butt sidewise therefrom and to clean said adjacent faces.
- 35 18. In a tobacco stemming machine, the combination with a series of co-acting two-part continuously traveling stem butt grippers said grippers being arranged to open and close in directions coincident with their path of travel, of rotatory means operative in a fixed position and adapted to pass be-
- tween and engage adjacent faces of the parts of said grippers while open to eject a stem butt sidewise therefrom and to clean said adjacent faces.
- 40 19. In a tobacco stemming machine, the combination with a series of co-acting two-part continuously traveling stem butt grippers said grippers being arranged to open and close in directions coincident with their path of travel, of a brush adapted to pass between and engage adjacent faces of the parts of said grippers while open to eject a stem butt sidewise therefrom and to clean said adjacent faces.

In testimony whereof, I have signed my name to this specification in the presence of two subscribing witnesses.

CHARLES F. LINDH.
